UNITED STATES PATENT OFFICE

2,473,787

JAW ADJUSTING DEVICE FOR PIPE
WRENCHESRaymond Alexander Conn, Springfield,
Nova Scotia, Canada

Application July 5, 1947, Serial No. 759,186

2 Claims. (Cl. 81—102)

1

This invention relates to improvements in a jaw adjusting device for a pipe wrench and appertains particularly to one having novel mechanism for holding the jaws in the desired position yet allowing of their simple and rapid readjustment.

An object of the invention is to provide a pipe wrench of the character described wherein the adjustable and loosely pivoted jaw is held in adjusted position by a spring urged bolt subject to retraction by a lever member conveniently located in the handle of the wrench.

A further object of the invention is the provision of a bolt locking mechanism for the adjustable and loosely pivoted jaw that is free to teeter without danger of binding, as the loose jaw hinges.

A still further object of the invention is the provision of a fast acting wrench of the nature and for the purpose described, that is characterized by structural simplicity, durability, ease of operation and positive action and that being capable of manufacture at reasonable cost is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a side elevation of the tool;

Figure 2 is a sectional elevation of the head thereof with the side plate removed to expose the 40 jaw-locking bolt and its actuating mechanism; and

Figure 3 is a transverse section through the wrench head, along the line 3—3 of Figure 2, in the direction indicated by the arrows.

The tool consists essentially of a handle member, one end of which serves as the fixed jaw; a movable jaw slidable with respect thereto and a locking device engageable with said movable jaw to hold it in the desired adjustment. Though useable to hold nuts, bolt heads and the like, this wrench is primarily intended as a pipe wrench and so the movable jaw is supported in such manner as to afford it a limited hinging action with respect to the fixed jaw whereby a tighten-

2

ing grip is obtainable on a pipe or similar article. It is to allow the jaws this relative hinging and provide a novel and ingenious locking mechanism for such movable jaw, operable in the handle of the wrench, that the instant invention is particularly directed.

The handle 5 which may have an open faced recess or be formed in laterally separable halves, is shown in the illustrated embodiment as having a solid stock and a lock-accommodating, Z-shaped recess 6 near its upper end normally covered by a face plate 7. Beyond the recess, the handle part is terminally widened to provide the integral fixed jaw 8.

Straddling the handle 5, just below the jaw head 8, and opposite the open upper end of the Z-shaped recess 6, is a guide yoke 9 in which the L-shaped movable jaw 10 is slidable longitudinally, substantially parallel with the handle 5, and with its gripping head overlying and confronting the fixed jaw 8 in the usual relationship. The spaced arms of the yoke 9 disposed over opposite sides of wrench stock 5 are hingedly connected thereto by a transverse pivot such as the bolt and nut assembly 11. The hinging or teetering this yoke is allowed is limited by the projecting angular shoulders 12 above and below it on the wrench handle 5.

To accommodate the stem of the movable jaw 10, slidable through it, the saddle or guide yoke 9 has a vertical passageway 14 and also a communicating horizontal passageway 15 approximately midway thereof that is extended vertically in both directions as it meets the former one. The inner edge of the shank of this movable jaw 10 is toothed as at 16 for normal engagement by a similarly toothed bolt 17 accommodated in the horizontal passageway 15; the vertical extension of the passageway being to receive the enlarged toothed head of the bolt. The inner end of the bolt stem is increased in height and provided with a longitudinal slot 18 to pass the pivot bolt 11, the slot having considerably more height than the diameter of the pivot since the bolt 17 besides being retractable horizontally must move vertically when the guide yoke hinges.

An L-shaped lever 19 with its toe 20 protruding through the open lower end of the plate-covered Z-shaped recess 6 in the handle, rises vertically 50 in the accommodating pocket and pivotally connects at its upper end to the inner end of the stem of the locking bolt 17 by a rivet pin 21 or the like. About midway of its height the lever has an elongated vertical slot 22 by which it slides and teeters on a transverse pin 23.

A leaf spring 24, anchored at its upper end as in the underside of the fixed jaw 8, normally bears against the inner end of the stem of the locking bolt 17, serving to hold it securely in engagement with the toothed stem of the sliding jaw 10.

This wrench is particularly easy to use because the control of the adjustable jaw is located well down in the handle and within convenient reach of the hand of the user holding the tool. It is only necessary with the thumb of the right hand, supporting the tool, to depress the lever toe or button 20 and with the left hand to close the jaws to fit the work and then release the right thumb pressure on the button 20 to have the wrench instantly adjusted. As the wrench is rotated, the movable jaw 10 and its guide yoke 9 hinge slightly, tightening the grip of the jaws on the pipe or work engaged but such hinging is not interfered with by the novel locking mechanism since the stem of the lock bolt 17 is so slotted as to allow plenty of clearance with the pivot 11 and its inner end can slide freely along the length of the engaging leaf spring 24 while the lever 19 is free to move vertically on the pin 23 and the opening at the lower end of the recess 6 has adequate height for the lever toe or button 20 to ride in.

From the foregoing description taken in connection with the accompanying drawings, it will be manifest that a handy pipe wrench capable of simple and rapid adjustment is provided that will fulfill all the necessary requirements of such a device but as many changes could be made in the above description and many apparently widely different embodiments of the invention may be constructed within the scope of the appended claims without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A pipe wrench comprising a handle, a fixed jaw on an end thereof, a guide yoke hingedly connected by a transverse pivot to said handle near the fixed jaw end thereof, a movable jaw 10 slidable in said guide yoke, a spring-urged bolt engageable with said jaw, slidably supported in said guide yoke and extending into said handle, said bolt being slotted to encompass the guide yoke pivot permitting it to both slide and hinge with its supporting guide yoke, a lever housed in said handle and longitudinally slotted approximately midway of its length and having its upper end pivotally attached to the inner end of said bolt and its lower end protruding from said handle, and a transversely disposed pivot pin extending through the slot in said lever on which said lever may both slide and teeter.

2. A pipe wrench comprising a handle, a fixed jaw on an end thereof, a Z-shaped recess in said handle opening through to one side of said handle just under said fixed jaw and also well down on the opposite side of said handle, a closure plate normally covering said recess, a guide yoke pivoted to said handle opposite the upper end opening of said recess, a movable jaw 10 slidable in said guide yoke, a spring-urged bolt slidably in said guide yoke and having one end portion normally engaging said movable jaw, its other end portion extending into said recess, a sliding and teetering lever housed in said recess, pivotally attached at its upper end to said bolt and having a toe at its lower end protruding through the lower side opening of the recess in said handle.
